UNITED STATES PATENT OFFICE.

FRANK L. FISHER, OF MILWAUKEE, WISCONSIN.

CAR-DOOR LOCK.

Application filed May 8, 1922. Serial No. 559,272.

To all whom it may concern:

Be it known that I, FRANK L. FISHER, a citizen of the United States, and resident of Milwaukee, in the county of Milwaukee and State of Wisconsin, have invented certain new and useful Improvements in Car-Door Locks; and I do hereby declare that the following is a full, clear, and exact description thereof.

10 This invention relates to a car door locking device.

As is well known, burglary of freight cars occurs most commonly when the cars are made up in trains and either at rest in the freight yard, or while in motion on the roadway. The reason for this is that the cars, when disconnected from each other, are usually attended by freight handlers in the regular employ of the company, so that 20 burglary or theft is not likely to occur at this time.

The invention comprises a car door having a series of recesses therein, a spring urged locking bolt, manually operable cam 25 means for retracting a locking bolt, and means operating when the coupling knuckle is in coupling position to prevent operation of the manually operable camming means. When the coupling knuckle is in uncoupled 30 position, the manually operable means may be actuated to retract the locking bolt.

The object of the invention is the provision of devices operative to prevent a door from being unlocked while one car is coupled to another, yet manipulable in a convenient manner when the car is uncoupled to unlock a door. The manually operable means is conveniently disposed with respect to the door, so that the door may be pushed 35 to a proper closed position and the resilient means for urging the locking plunger permitted to operate. By having the locking plunger manually controllable and by the provision of resilient means for urging the 40 locking plunger into locking position, such danger of damaging the door as would arise from the operation of directly actuatable locking means operable by the coupling knuckle, is eliminated. If the plunger were driven 45 outwardly positively, it might contact with the door and not be received in a recess. In 50 this case damage would result.

With the above and other objects in view, which will appear as the description proceeds, my invention resides in the novel construction, combination and arrangement of

parts, substantially as hereinafter described and more particularly defined by the appended claims, it being understood that such changes in the precise embodiment of the 60 herein disclosed invention may be made as come within the scope of the claims.

In the accompanying drawings, I have illustrated one complete example of the physical embodiment of the present invention constructed according to the best mode 65 I have so far devised for the practical application of the principles thereof, and in which:

Figure 1 is a cross section through a car 70 showing an embodiment of the invention in plan, the coupling head being shown partly in section. The view is taken substantially on the line 1—1 of Figure 3.

Figure 2 is a cross section taken on the 75 line 2—2 of Figure 3.

Figure 3 is a sectional view showing the knuckle coupling in unlocked position.

Figure 4 is a cross section on the line 4—4 of Figure 1, bringing out the character of 80 the locking bolt.

The door 10 is slidable along car side 11 and is provided with a series of recesses 12. To the inner face of side 11 chambered support 13 is secured. The housing and side 85 11 have openings through which locking plunger 14 is movable. The inner end of the plunger moves in an opening in wall 15. The plunger is urged outwardly by means of a helical spring 16 contacting with a collar 17 carried by the plunger.

In Figure 1 the door 10 is shown in closed position. The door may be slid to this position, riding along the bevelled end of the plunger 14, which is inclined to permit 95 movement of the door in one direction, but to prevent reverse movement. The locking plunger has an opening 18 therein. Bracket bearings 19 and 20 rotatably support a shaft 21 along the inner side of the car. Rigid 100 with the shaft is a cam 22 adapted, when plunger 14 is in locking position, to project into the lower part of opening 18. The shaft 21 is rotatable by a bell crank 23 having a handle 24 thereon, the handle projecting through an opening 25 in the car floor.

The movement of the handle 24 in a counter clockwise direction, looking at Figure 2, causes cam 22 to move upwardly in opening 18, retracting locking plunger 14. When 110 the hand is removed from handle 24, spring 16 urges plunger 14 outwardly, cam 22 be-

ing pushed downwardly by the plunger in its movement. Thus conveniently manipulable means are provided for unlocking the door, the means being adapted on the removal of the hand of the operator to permit locking plunger 14 to return to normal locking position.

Bell crank 23 carries at one end flanges 26 adapted to receive therebetween an end of lever 27 pivotally mounted at 28 to wall 29. The end of the lever carries a shoe 30 overlying an end of an upwardly extending arm 31 of the lever 32, pivotally mounted on rod 33 to coupling head 34 which carries coupling knuckle 35, having a tail 36 adapted to overly in locking position the contiguous end of lever 32.

Figure 1 shows the relationship of parts when the knuckle 35 is in coupling position. Lever 32 is then substantially immovable and shoe 30 on lever 27 is prevented from moving downwardly. It is, therefore, impossible to move handle 24 in a counter-clockwise direction hence cam 22 cannot be moved upwardly in opening 18. It will be apparent, therefore, that when the car is coupled to another car, the locking plunger 14 cannot be moved to unlocking position.

When, however, coupling knuckle 35 is in uncoupled position, as shown in Figure 3, tail 36 does not prevent the upward movement of the adjacent end of lever 32 so that arm 31 may move downwardly, as, also, may shoe 30. The handle 24 may then be moved in a counter-clockwise direction, looking at Figure 2, and cam 22 may thus be moved upwardly in opening 18, retracting locking bolt 14. It is thus apparent that when the car is uncoupled, the position of knuckle 35 permits the manual operation of handle 24 and the unlocking of the door 10. The door 10 may be slid to a desired position and handle 24 may be released by the operation and plunger 14 may be permitted to engage 45 in a recess 12. The convenient manual

manipulation of handle 24 thus permits the ready centering of the end of locking plunger 14 in a recess 12. Thus the locking of the door is not attendant with any danger of damage, such as would occur if a direct and positive locking means were provided actuatable on the coupling of the car to drive a locking plunger laterally. The locking plunger might not be received in a recess under such circumstances and damage might be done.

I claim:

1. The combination of a car, a door, means for locking said door, manually operable means for cooperating with said first mentioned means to unlock said door, a coupler head, a coupler knuckle, and means operable when said knuckle is in coupling position to prevent operation of said manually operable means. 65

2. The combination of a car, a door, means for locking said door, manually operable means for cooperating with said first mentioned means to unlock said door, a coupling head, a coupler knuckle, and means operable when said coupler knuckle is in coupling position to prevent operation of said manually operable means, said last mentioned means permitting operation of said manually operable means when said coupling 75 knuckle is in uncoupling position.

3. The combination of a car, a coupler head, a coupler knuckle, a door having recesses therein, a locking plunger, resilient means urging said plunger into one of said 80 recesses, manually operable means for retracting said locking plunger, and means operative when said knuckle is in coupling position to prevent operation of said manually operable means. 85

In testimony that I claim the foregoing I have hereunto set my hand at Milwaukee, in the county of Milwaukee and State of Wisconsin.

FRANK L. FISHER.
